TRAILER AWNING UNIT

Charles D. Shelton, 8601 Cherry Lane,
Westminster, Colo. 80030

Filed Sept. 12, 1968, Ser. No. 13,514

Term of patent 14 years

Int. Cl. D12—14; D21—05

U.S. Cl. D14—3

FIG. 1 is an isometric rear view of a trailer awning unit showing my new design, in extended position.

FIG. 2 is a side elevational view, on a reduced scale, of the arrangement shown at FIG. 1.

FIG. 3 is an isometric view similar to FIG. 1, but with the awning retracted.

FIG. 4 is a side elevational view of the awning mounting, on an enlarged scale.

FIG. 5 is a plan view of one side of the awning mounting.

The trailer shown fragmentarily in broken lines is included for illustrative purposes only. The side of the design not shown is a mirror image of the disclosed side.

I claim:

A design for a trailer awning unit, as shown and described.
